UNITED STATES PATENT OFFICE.

CHARLES W. RAMSAY, OF BROOKLYN, NEW YORK.

APPARATUS FOR TREATING FERMENTED, FERMENTABLE, OR DISTILLED LIQUIDS.

SPECIFICATION forming part of Letters Patent No. 313,237, dated March 3, 1885.

Application filed March 31, 1884. (No model.)

To all whom it may concern:

Be it known that I, CHARLES W. RAMSAY, of Brooklyn, in the county of Kings and State of New York, have invented a new and useful 5 Apparatus for Treating Fermented, Fermentable, or Distilled Liquid, for the purpose of preventing any deleterious fermentation, also for improving and aging the liquid; and I do hereby declare the following to be a full and 10 clear description of the invention.

The nature of this invention consists in the construction of a machine so that the liquid to be treated may be delivered into it at or near the hub or center of a set of revolving 15 beaters or drivers, from which point of inlet the fluid under treatment is then driven around by the said revolving beaters or drivers and by the centrifugal action of the same, subjected to an infinite number of severe shocks 20 or concussions, which in the first place atomize or drive the fluid under treatment into an exceedingly fine vapor or spray, and in this attenuated form impart to it severe shocks or concussions delivered by the said beaters 25 to every atom of the vaporized fluid, thereby destroying completely any germ-life that may be contained in the liquid, and in the case of whisky and other distilled liquids breaking up the oil and other globules, which are thereby 30 allowed to permeate the whole mass under treatment, and in this state atmospheric air or pure oxygen, if added to the vapor produced in the machine, will rapidly age or ripen the mass under treatment and render it 35 fit for use.

The invention will be readily understood by reference to the accompanying drawings, of which Figure 1 is a transverse sectional elevation of the machine. Fig. 2 is a longitudinal sectional elevation of the machine.

The machine consists of one or more treating-chambers, A, within each of which, eccentrically placed, is a set of rotary drivers or beaters. The said treating-chambers A have helical or nearly helical sides and parallel ends, and are made perfectly air-tight, except as to their inlet and outlet apertures. The said drivers or beaters consist of two disks, B C, with teeth or arms b d projecting from their contiguous faces, so as to interlock with each other, the disks B C being attached to separate driving-shafts B' C' and

rotated in opposite directions. The arms or beaters proper, b c, are respectively rotated in opposite directions, and consequently deliver smart blows or concussions to all the atoms of fluid received by one set of the arms or beaters from the other set. The driving-shafts B' C' each have two bearings, D D, outside of the casing or housing A, and each has 55 its respective driving-pulley b' c', by which suitable belting properly arranged drives the said shafts with their attached disks in opposite directions. The disks B C are secured to their respective shafts at their inner ends, 60 which are separated a short distance, so that they will readily free each other, and the disk B is a simple plain disk; but the disk C is made with an annular opening, c², in its side for the reception of the feeding-pipe E, which 65 delivers the fluid to be treated inside of the said disk C and near its hub. The annular opening c² in the side of the disk C necessitates the forming the said disk with an inner flange or hub-plate, c³, connecting the hub c⁴ with the 70 annular connecting-plate c⁵, as shown clearly in Fig. 2, and the outer edge of the said connecting-plate c⁵ is attached to and carries the disk C proper. This construction forms an interior hub-pocket, C², as is clearly shown 75 in Fig. 2, and into this hub-pocket the fluid to be treated is delivered by the feed-pipe E, and from this said hub-pocket the fluid passes through suitable apertures, c⁶, in the circular connecting-plate c⁵, into the space between 80 the disks B C, where it is received by the beaters or arms b c.

The beaters or arms b c are firmly secured to their respective disks B C, and project from the inner faces of their respective disks nearly 85 to the face of the opposite disk, and they are arranged in sets, as shown in Fig. 2, each set placed in annular form and commencing at the hub of the machine. The first set of these arms or beaters is attached to one of the disks, 90 and the next set to the other disk, and so on to the outermost set of teeth or beaters, each alternate set being attached to one disk, and the intermediate and interlocking sets attached 95 to the other disk, thereby causing each alternate set to rotate in an opposite direction to both of its adjacent fellies, as shown by the arrows in Fig. 1. This arrangement causes all fluid passing through the machine to be 100

thrown or driven from one set of the arms or beaters to the next outward set with great violence, and the arms or beaters are to be numerous enough to receive and act upon every atom of material fed into the machine, and the centrifugal action of the beaters causes the fluid to pass through the machine from the hub outwardly, the last set of beaters driving the fluid atoms with great violence against the surrounding casing A. As has before been stated, this surrounding casing is made with helical or nearly helical sides, as is shown in Fig. 1, and its ends are made straight and parallel with the disks B C, which revolve with it.

In arranging for the proper position of the disks within the housing A, care will be taken to place one side of the said disks in close proximity to that side of the housing next above the outlet F, thereby making the treating-chamber gradually enlarge from its smallest opening between the beaters and the casing A at the point α toward the outlet F, thus causing the delivery of the final blows of the beaters upon the fluid under treatment with supreme effect, the gradually-enlarging chamber A giving the required accommodation for the enlarging volume of the fluid by reason of the beaters driving it into an atomic or porous state, thus materially increasing its volume. The outlet-duct F is made to slope slightly downward and gradually enlarging toward its outlet end.

The fluid to be treated is first placed in a closed tank, G, at a sufficient elevation to be conducted through the pipe E into the interior of the treating-disks B C. The outlet F leads to a closed receiving-chamber, H, into which the treated fluid in a vaporous state is discharged. Where more than one treating-chamber is used, the receiving-chamber H of the first section of the machine becomes the feeding-tank for the next treating-chamber, and the pipe E, leading from it to the second treating-chamber, acts precisely like that above described. In this manner there may be as many of the treating-chambers A as required to perform the vaporization and concussion desired upon any fluid which it is required to treat in this machine.

For such liquids as require oxidization or aging, a suitable machine or compressor, I, is used, from which said machine a pipe, J, leads to the treating-chamber A or its inlet-pipe E, and discharges compressed atmospheric air or oxygen gas into the fluid under treatment, which said fluid is thereby oxidized or aged while the said fluid is in the machine in a vaporous state.

In introducing the air or gas into the machine, care must be taken to have the incoming flow of air or gas moving in harmony with the moving current of fluid into or in the machine, so that neither current may interrupt the other.

I am well aware that a pair of disks armed with interlocking teeth on their adjacent faces and revolved in opposite directions in a closed case is not new, as such a construction is shown in an English patent on an attrition-mill for grinding grain and other hard substances, and also in a German patent on a malt-mashing machine, the last-named machine being provided with a case of nearly helical form, but provided with an enlarging area opening upward, and hence not at all adapted to the purposes of my machine for treating fluids; consequently I lay no claim, broadly, to the disks with interlocking teeth; but

What I do claim is—

In combination with a closed chamber of helical or nearly helical formation having its enlargement downwardly, and an outwardly-enlarging ejection-pipe taken as nearly as possible from the lowest part of said chamber, a pair of rotating disks revolved in opposite directions, and their adjacent faces armed with interlocking teeth for striking with sharp blows the atoms of fluid passing through the machine, and an induction-pipe leading from a reservoir above and without the treating-chamber to the interior thereof through an annular opening in the side of the hub of one of the revolving disks.

CHARLES W. RAMSAY.
